UNITED STATES PATENT OFFICE.

FLORENCE I. HAMMOND, OF CHICAGO, ILLINOIS.

DESIGN FOR A RING.

Application filed March 23, 1925. Serial No. 12,853. Term of patent 14 years.

To all whom it may concern:

Be it known that I, FLORENCE I. HAMMOND, a citizen of the United States, residing at Chicago, in the county of Cook and State of Illinois, have invented a new, original, and ornamental Design for Ring, of which the following is a specification, reference being had to the accompanying drawing, forming a part thereof.

Fig. 1 is a perspective view of the ring, and

Fig. 2 is a bottom plan view of the ring.
I claim:

The ornamental design for a ring as shown.

In witness whereof, I hereto subscribe my name this 20th day of March, 1925.

FLORENCE I. HAMMOND.
